(57) CLAIM

The ornamental design for an egg beater holder as shown and described.

DESCRIPTION

FIG. 1 is a front, right and bottom perspective view of an egg beater holder, showing my new design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and bottom perspective view of the egg beater holder of FIG. 1 shown in another configuration of use.

The dashed broken lines depict portions of the egg beater holder that form no part of the claimed design.
